Primary Examiner — George A Bugg*Assistant Examiner* — Ji Sun Yoon(74) *Attorney, Agent, or Firm* — Global IP Counselors, LLP(57) **CLAIM**

The ornamental design for a cooler and warmer box as shown and described.

DESCRIPTION

FIG. 1 is a front, right and top perspective view of a cooler and warmer box showing our new design;

FIG. 2 is a rear, left and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines in the drawings illustrate portions of the cooler and warmer box which form no part of the claimed design.

1 Claim, 8 Drawing Sheets
